CLAIM

The ornamental design for a propeller fan, as shown and described.

DESCRIPTION

FIG. 1. is a front perspective view of the front, right, and bottom sides of a propeller fan showing a first embodiment of our new design;

FIG. 2. is a front view thereof;

FIG. 3. is a rear view thereof;

FIG. 4. is a left side view thereof;

FIG. 5. is a right side view thereof;

FIG. 6. is a top plan view thereof;

FIG. 7. is a bottom view thereof;

FIG. 8. is an enlarged view at a part 8 of FIG. 1;

FIG. 9. is a front perspective view of the front, right, and bottom sides of a propeller fan showing a second embodiment of our new design;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom view thereof; and,

FIG. 16 is an enlarged view at a part 16 of FIG. 9.

The broken lines shown represent unclaimed subject matter of the propeller fan and form no part of the claimed design. The dash-dot lines represent the boundary between the claimed design and unclaimed design.
